ELECTRICITY CONDUCTOR UNIT

Louis G. Morten, Teaneck, N. J., assignor to John B. Pierce Foundation, New York, N. Y., a corporation of New York

Original application December 27, 1933, Serial No. 704,189. Divided and this application November 24, 1939, Serial No. 305,767

1 Claim. (Cl. 174—74)

This invention relates to improved electrical wiring systems, and particularly to improved conductor carrying units arranged for serialism interconnection to afford a continuous electrical circuit.

The present application is a division of my co-pending application Serial No. 704,189, entitled "Electricity conductor units," and now U. S. Patent No. 2,218,545, dated October 22, 1940.

It is an object of the present invention to provide "run" conductor units and "connector" conductor units for serialism interconnection, the said "run" and "connector" units having means affording a complete insulation of the conductor means of such interconnected units in the zone of interconnection thereof, to eliminate danger of accidental short circuiting of the conductor means.

It is a further object of the present invention to provide electricity conductor units for serialism interconnection, said units having socketed end portions of which the walls are integral with the body portion and form a continuous enclosure co-extensive with the external faces of the body portion of the units. Such socketed end portions receive, and completely envelop, male end portions of the therewith interconnected conductor units.

In the accompanying drawing, of which the figures are perspective representations:

Fig. 1 shows an outlet-provided connector unit having a male connection end and a female connection end for serialism interconnection with electricity conductor "run" units;

Fig. 2 illustrates a portion of an electric circuit, showing an angle "connector" unit embodying female connection ends and a therewith interconnected "run" unit having male connection end portions mechanically interconnecting with said "connector" unit; and

Fig. 3 illustrates a T "connector" unit embodying the present invention.

Referring to the drawing for a more detailed description of the invention, the electric circuit shown in Fig. 2 incorporates an angle or corner connector" unit A7, to which is mechanically interconnected a "run" unit A8. A second run unit (not shown) may be inserted in the vertically disposed socketed end.

Desirably, the body 122 of connector unit A7 and the body 63 of run unit A8 is wholly of electrical insulation material. The respective body portions incorporate any desired plurality of electricity conductors.

Connector units A7 may be provided at either both ends, with socket facilities for male and

female interconnection with male connection ends of adjacent run units or outlet provided connector units, such male and female interconnection being characterized by substantial depth of insertion of the male element into the complementary socket and by an integral socket wall completely encompassing the male projection portion and thereby affording protection against accidental contact with the electrical conductors at the point or points of serial interconnection of the conductor units from any exposed face of the interconnected wiring system.

The sockets 123, 123 of connector unit A7, as appears in Fig. 2, are defined by the external wall surfaces of the main body portion of such unit, and hence the connector unit is characterized by uniformity of contour, devoid of offset surfaces or break. The illustrated electricity conductors within unit A7 terminate in sockets 57 of electrically conducting material, the terminal openings of such sockets being flush with the base wall of sockets 123.

The run units, typified by A8 of Fig. 2, comprise a body 63, desirably wholly of electrical insulation material and having a male connection end portion 124 so dimensioned that it engages snugly with the socket 123 of conductor unit A7. Desirably such male connection portions are symmetrical with the major axes of the body 63 of the run unit, and the lateral faces of such male connection portions are, therefore, offset with respect to the corresponding lateral faces of the body portion, the degree of such offset being substantially equal to the thickness of said female socket walls. As shown in Fig. 2, the connector and run units are preferably of identical contour and cross sectional area, thus affording an interconnection which is without noticeable break or offset, and achieving visual continuity of the interconnected units.

The electricity conductors of each run or connector unit having a male connection end portion, terminate in projections or pin-like extensions 55 which project from the end surface of the male connection end, as indicated at 124 of run unit A8 and such extensions 55 are disposed in alignment with the respective electrically conductive sockets 57 of the connector unit. Pins 55 are arranged for a snug frictional engagement with the inner wall of the sockets 57, such frictional engagement insuring proper electrical conduction between the conductors of the respective interconnected units.

Mechanical interengagement of a run unit with a connector unit is accomplished by the snug fit of the respective male and female portions there-

for, such snug fit being rendered additionally effective for mechanical interengagement by the relatively great area of engagement of the extension portion 124 with its associated socket 123.

The embodiment of Figure 1 illustrates an outlet-provided connector unit 141, the outlets thereof being designated 178, 180. Such connector unit may have a socketed end portion 177, similar to that described with respect to Fig. 2, embodying electrical conductor sockets 57 terminating at the base of such socket portions as shown. The opposite end of such conductor unit may be provided with a male extension portion 177a and projecting conductors 55, for interconnection with the socketed portion of a second connector unit, or with the socket portion of a run unit, as illustrated, such run unit being provided with socketed conductors, as will be understood.

Fig. 3 indicates a T unit by means of which a vertical branch circuit may be derived from a run circuit. Such T unit, designated 125, may have two of its ends provided with sockets, such as 126, 128, with an end provided with a male connection extension, designated 126a, for connection with the socketed end of a run unit, as described with respect to Fig. 1.

Whereas I have described my invention by reference to specific forms thereof, it will be understood that many changes and modifications may be made without departing from the spirit of the invention.

I claim:
An electricity conductor unit adapted for male

and female seriatim interconnection with other conductor units having substantially identical facial configuration and dimension and substantially identical end configurations, comprising a body of rigid insulation material having fixed therein a plurality of electricity conductors arranged in mutually spaced insulated relationship and terminating at the ends of said body in electricity conductor means adapted for electrical connection with electricity conductors of adjacent units, said body of rigid insulation material having at one end a deep polygonal socket formation disposed symmetrically with respect to the body of the unit and characterized by external walls which are co-planar continuations of the walls of the main body of the unit, and at another end with a polygonal extension portion symmetrical with the body of the unit and having an external configuration matching the configuration of the socket and a length of extension equal to the depth of the socket, the lateral walls of said polygonal extension being inwardly offset with respect to the walls of the main body of the unit to an extent equal to the thickness of the walls of the socketed end, and each of said extension walls being in the plane of the corresponding wall of the socketed end whereby the surfaces of the polygonal extension of one unit will be in contact with the socket walls of an adjacent unit at all relative positions of insertion of the extension into said socket.

LOUIS G. MORTEN.
